(57) **CLAIM**

The ornamental design for a three-dimensional anatomic first metatarsal-phalangeal joint replacement, as shown and described.

DESCRIPTION

FIG. 1 is a top front perspective view of a three-dimensional anatomic first metatarsal-phalangeal joint replacement showing my new design;

FIG. 2 is a top rear perspective view thereof;

FIG. 3 is left view thereof;

FIG. 4 is a right view thereof;

FIG. 5 is a top view thereof;

FIG. 6 is a bottom view thereof;

FIG. 7 is a front view thereof;

FIG. 8 is a back view thereof;

FIG. 9 is an exploded top front perspective view thereof;

FIG. 10 is an exploded bottom front perspective view thereof;

FIG. 11 is an exploded top rear perspective view thereof;

FIG. 12 is an exploded bottom rear perspective view thereof;

FIG. 13 is a cross sectional view thereof taken along line 13-13 in FIG. 9; and,

FIG. 14 is cross sectional view thereof taken along line 14-14 in FIG. 9.
